UNITED STATES PATENT OFFICE.

JULES H. STEAN, OF WORCESTER, MASSACHUSETTS, ASSIGNOR OF ONE-HALF TO
COURTNEY BURRAGE, OF WORCESTER, MASSACHUSETTS.

DESIGN FOR A CIGAR-PERFORATOR.

52,151.

Specification for Design.

Patented July 2, 1918.

Application filed April 24, 1918. Serial No. 230,593. Term of patent 7 years.

To all whom it may concern:

Be it known that I, JULES H. STEAN, a citizen of the United States, residing at Worcester, in the county of Worcester and State of Massachusetts, have invented a new, original, and ornamental Design for a Cigar-Perforator, of which the following is a specification, reference being had to the accompanying drawing, forming part of this specification, in which—

Figure 1 is a perspective view of a cigar perforator, showing my new design, and Fig. 2 is a plan view thereof.

I claim:—

The ornamental design for a cigar perforator, as shown.

JULES H. STEAN.
